UNITED STATES PATENT OFFICE.

JOHN GEER, OF LONDON, ENGLAND.

DESIGN FOR A BOOK-LEAF.

SPECIFICATION forming part of Design No. 33,565, dated November 13, 1900.

Application filed January 15, 1900. Serial No. 1,568. Term of patent 3½ years.

To all whom it may concern:

Be it known that I, JOHN GEER, a subject of the Queen of Great Britain, residing at Farringdon Road, London, England, have invented and produced a new and original Design for a Book-Leaf, of which the following is a specification, reference being had to the accompanying drawing, forming part thereof, in which is illustrated an elevational view of the book-leaf, showing my new design.

As shown in the drawing, the leading or material feature of my design consists in curving the upper and lower edges of the book-leaf A in a concave manner and scalloping or

corrugating the longer edge of the book-leaf 15 at the front thereof, so as to produce alternate concavities B and convexities C.

The back edge D of the book-leaf is of ordinary straight form.

Having described my invention, what I 20 claim as new, and desire to secure by Letters Patent, is—

The design for a book-leaf as herein shown and described.

JOHN GEER.
